WELDED SHIP

George Pamphilis, Hoboken, N. J., assignor to
 Argonaut Engineering Corp., Hoboken, N. J., a
 corporation of New Jersey

Application August 9, 1944, Serial No. 548,728

4 Claims. (Cl. 114—79)

This invention relates to new and useful improvements in welded ships, and has more particular reference to an improved reinforcement for the plates thereof.

More specifically, the invention proposes the use of a plurality of substantially horizontal metallic strips vertically spaced from each other and welded upon the ship's hull for strengthening same longitudinally and for acting as a stabilizer. The strips engage the water and materially reduce rolling of the ship.

The invention proposes to extend the reinforcing strips from stern to bow of the ship, or a lesser distance if desired.

It is pointed out that the more strips used, the better the reinforcement and the stabilizing action. However, it is suggested that there be one strip for approximately each two feet of height of the hull, or one strip may be used for each horizontal seam of the plates forming the hull, or the strips may be used in between the seams.

The invention further contemplates several modified forms.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an illustration of a ship provided with reinforcements in accordance with this invention.

Fig. 2 is an enlarged detailed front elevational view of the ship shown in Fig. 1.

Fig. 3 is a fragmentary enlarged vertical sectional view taken on the line 3—3 of Fig. 2.

Fig. 4 is a fragmentary enlarged vertical sectional view taken on the line 4—4 of Fig. 2.

Fig. 5 is a fragmentary perspective view of a piece of one of the reinforcing strips.

Fig. 6 is a fragmentary sectional view similar to Fig. 1 but illustrating a modified form of the invention.

Fig. 7 is another fragmentary sectional view similar to Fig. 3 but illustrating still another modified form of the invention.

Fig. 8 is a fragmentary perspective view of the parts shown in Fig. 7, certain of the parts being separated for illustrative purposes.

The reinforcement for welded ships, in accordance with this invention, is intended for

welded ships having an interior frame 10 and hull plates 11 welded to each other and mounted on the frame 10. A plurality of substantially horizontal metallic strips 12 are vertically spaced from each other and are mounted on the hull plates 11 and preferably extend from the bow to the stern of the ship, and preferably all the way down to the keel. In Figs. 1 and 2, a ship 14 of any design and construction is shown provided with the reinforcement strips 12.

Each of the strips 12 is secured to the hull plates 11 by welding material 15 along the top and bottom edges. Each of the strips 12 is furthermore secured to the ship at horizontally spaced points by rivets 16. These rivets are passed through the strips 12 through the plates 11, and also through the frame 10.

Several modified forms of the invention are proposed. In the form disclosed particularly in Figs. 3—5, the strips 12 are set over the horizontal seams of adjacent hull plates. For example, the hull plates 11^a and 11^b are provided with a horizontal welded seam 17. The strip 12 is formed with a horizontal recess 18 for engaging the seam 17. In this way, the strips 12 reinforce the horizontal seams of the hull.

It is proposed that the strips 12 be horizontally spaced from each other, preferably two feet apart, though this distance may be varied in accordance with design. It is further proposed that each strip 12 be approximately one inch thick and three inches high, though here again these dimensions may be varied. With the particular design proposed it will be found that the reinforcement strips 12 not only structurally reinforce the hull of the ship but also act as stabilizers to prevent or reduce rolling of the hull.

In Fig. 6 a modified form of the invention has been disclosed which is very similar to the prior form, distinguishing merely in the fact that reinforcement strips 12 are mounted upon the hull plates 11 at points in between the horizontal weld 17 of the hull plates. The strips 12' are mounted in position by welded material 15 along the top and bottom edges. At spaced horizontal points, the strips 12' are also securely held by rivets 16 which are passed through the hull plates 11 and through the frame 10. Because the reinforcement strips 12' are not mounted over the seams of the hull plates, they do not need recesses at the back for accommodating the welded seams.

In Figs. 7 and 8 another modified form of the invention is shown which is very similar to the first form of the invention, distinguishing merely

ly in the construction of the reinforcement strips 12". In this form of the invention each reinforcement strip 12" is formed from two separate strip sections. There is a narrow bottom strip section 12^a and a much wider top strip section 12^b. The bottom strip section 12^a is formed with an outer top beveled face 20 and an inner groove 21. This bottom strip section 12^a is secured upon the hull of the ship with welding material 15 disposed within the groove 21. The top wide strip section 12^b has a beveled bottom edge complementary to and engaging the beveled outer edge portion 20^a of the bottom strip section 12^a for locking the top and bottom strip sections together. The top strip section 12^b is permanently secured to the hull by top welding material 15 along the top edge thereof.

In other respects this form of the invention is similar to that previously shown and like reference numerals identify like parts in each of the several views.

An improved method is also proposed for attaching the reinforcement strips 12" in position. It is proposed to provide a protecting cover strip 24 removably mounted upon the top of the beveled edge 20 and the bottom strip section 12^a. It is proposed to weld the strip section 12^a in position on the hull with the welding material 15. The purpose of the removable strip 24 is to protect the bevel 20 from accidental deposits of welding material. After the strip section 12^a is welded in position it is proposed that the removable strip 24 be removed. This removable strip may be removably held by soft solder at spaced points or by tacky material, or other adhesive material which may be easily opened. When the strip 24 is removed the edge 20 will be clean and will be ready to receive the top strip section 12^b which is then engaged in position. The top strip section 12^b is then securely fastened by the welding material and the rivets 16.

In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a welded ship having an interior frame

and hull plates welded to each other and mounted on said frame, a plurality of substantially horizontal metallic strips vertically spaced from each other and mounted upon said hull plates, at positions over the horizontal seams of said hull plates secured at their edges to said hull plates, said strips having recesses on their back faces into which the seams of the hull plates may engage, and rivets securing said horizontal strips to said hull substantially along their center lines preventing outward bulging of said strips between the secured edges.

2. In a welded ship having an interior frame and hull plates welded to each other and mounted on said frame, a plurality of substantially horizontal metallic strips vertically spaced from each other and mounted upon said hull plates, at positions over the horizontal seams of said hull plates secured at their edges to said hull plates, said strips having recesses on their back faces into which the seams of the hull plates may engage, and rivets securing said horizontal strips to said hull substantially along their center lines preventing outward bulging of said strips between the secured edges and which engage through the strips and the hull plates and said interior frame.

3. In a welded ship having an interior frame and hull plates welded to each other and mounted on said frame, a plurality of substantially horizontal metallic strips vertically spaced from each other and mounted upon said hull plates, each of said horizontal strips comprising a narrow bottom strip having an outer inwardly inclined beveled face and an inner groove, said bottom strip being welded by welded material within said groove, and a wide top strip having a bevel complementary to and locking into said bevel, and said wide top strip being welded and riveted upon said hull plates.

4. A method for reinforcing a welded ship consisting in welding a plurality of substantially horizontal narrow metallic bottom strips having an outer inwardly inclined beveled surface, said bottom strips being at vertically spaced positions from each other upon the hull plates of the ship by welding material placed within a top groove thereof and protected from engaging upon said outer top beveled surface by removable strips, removing said removable strips after said narrow bottom strips are welded in position, and engaging wide top strips upon said bottom strips, said top strips having interlocking faces with the bevel of said bottom strips, and welding said top strips in position.

GEORGE PAMPHILIS.
